UNITED STATES PATENT OFFICE.

ALBERT SELLE, OF NEW YORK, N. Y.

DESIGN FOR A SHADE AND CURTAIN HOLDER OR SIMILAR ARTICLE.

41,435.

Specification for Design.

Patented June 6, 1911.

Application filed March 17, 1911. Serial No. 615,126. Term of patent 7 years.

To all whom it may concern:

Be it known that I, ALBERT SELLE, a citizen of the United States, and resident of the city of New York, borough of Brooklyn, county of Kings, and State of New York, have invented a new, original, and ornamental Design for a Shade and Curtain Holder or Similar Article, of which the following is a specification, reference being had to the accompanying drawing, forming part thereof.

The figure is a perspective view of a shade and curtain holder, showing my new design therefor.

The design comprises a flat base portion with a supporting arm of open ornamental construction extending at right angles thereto, substantially as shown in the drawings.

I claim:

The ornamental design for a shade and curtain holder, or similar article, as shown and described.

ALBERT SELLE.
